UNITED STATES PATENT OFFICE.

JAMES GREENHALGH, OF PASCOAG, RHODE ISLAND.

HARNESS-FRAME FOR LOOMS.

Specification of Letters Patent No. 28,270, dated May 15, 1860.

To all whom it may concern:

Be it known that I, JAMES GREENHALGH, of Pascoag, in the county of Providence and State of Rhode Island, have invented a new 5 and useful Improvement in the Harness-Frames of Looms; and I do hereby declare that the following is a full, clear, and exact description of the same, reference being had to the accompanying drawings, forming part 10 of this specification, in which—

Figure 1 is a front view of a harness frame, constructed according to my invention. Fig. 2 is a transverse vertical section of the same in the line x, x , of Fig. 1. Fig. 15 3 is a horizontal section of the upper heddle bar. Fig. 4 is a transverse section of the upper heddle bar, on a larger scale than the other figures. Fig. 5 is a front view of a frame of the old construction.

20 Similar letters of reference indicate corresponding parts in all the figures.

My invention consists in a certain construction of the frames for the reception of wire heddles, whereby the ends of the wires 25 of the heddles of one frame are prevented catching against the next frames or their heddles and the heddles are kept stretched better than by the usual mode of securing them.

30 To enable others skilled in the art to make and use my invention I will proceed to describe it with reference to the drawings.

A, A' are the heddle bars, and B, B, the end-pieces of the frame, by which the said 35 bars are connected, and kept at the proper distance apart. The bars A, A', are made each of a straight strip of sheet-iron of the requisite length, and of suitable width, bent transversely into a nearly elliptical form, as 40 represented in Figs. 2 and 4, or to a quadrangular form leaving a narrow longitudinal opening a , between the edges. The end-pieces B, B, consist of pieces of flat bar-iron, and are inserted in the ends of the bars A, 45 A', and secured therein by rivets b, b, the narrow openings a , a , being brought opposite each other, that is to say, to the bottom of the upper bar A, and to the top of the lower bar A'. Each bar has a recess e, cut 50 in its inner side to make an opening, such as is shown at e, in Figs. 2 and 3, the said recesses being both at one end of the frame as shown in Fig. 1.

d, d , are two straight flat rods, one placed loosely inside each heddle bar and extending 55 not quite the whole length of the interior thereof. These rods may be inserted in the heddle bars at the ends thereof before the end-pieces are put in to make the frame, or may be made thin enough to pass through 60 the slots a, a , after the frame is complete.

C, C, are the heddles each made in the usual way of a single piece of wire folded in the middle of its length and twisted to form the eye h, in the middle, and to form 65 loops f, g, at the top and bottom for the rods d, d, to pass through. The loops g, are completed by twisting the ends of the wire together, as shown in Figs. 1 and 2.

To secure the heddles in the so constructed 70 frame, the rods d, d, are first placed inside the heddle bars and their ends brought into the recesses e, e, and the heddles are then placed, one at a time, between the said recesses, as shown in red outline at the left 75 hand of Fig. 1, and their loops f, g, slipped into the wide openings c, c, at the back of the said recesses, and passed over the ends of the rods, after which they are slid along the rods in the narrow openings a, a, from 80 which their loops f, g, cannot come out, as they are kept open by the rods d, d. The twisted ends of the wires which complete the loops g, g, being inside of the lower heddle rail, are protected and prevented 85 catching in the adjacent frames, and in this consists a great advantage over the old mode of securing them by rods i, i, passing through fixed eyes j, j, in the rails, as shown in Fig. 5. Besides this advantage the strain 90 of the heddles being sustained by the bars A, A', enables them to be kept extended better than they are by the rods i, i, which receive their strain in the old mode of securing them.

95 What I claim as my invention, and desire to secure by Letters Patent, is—

The combination of the hollow heddle bars A, A', and the rods d, d, inserted within the said bars to secure the loops at the ends of 100 the heddles, substantially as herein described.

JAMES GREENHALGH.
